COMBINED CLEANING EQUIPMENT CART AND STEP STOOL

Georgia Kreider, 608 Devonshire Drive,
Sturgis, Mich. 49091

Filed Apr. 10, 1967, Ser. No. 6,603

Term of patent 14 years

(Cl. D14—3)

FIG. 1

FIG. 2

FIG. 3

FIG. 4

FIG. 6

FIGURE 1 is a perspective view of a combined cleaning equipment cart and step stool embodying my new design;

The dominant features of the design are disclosed in solid lines.

I claim:

The ornamental design for a combined cleaning equipment cart and step stool, as shown and described.
